Philippe Baillau

UNITED STATES PATENT OFFICE.

PHILIPE BAILLAU, OF NEW YORK, N. Y.

THILL FOR TWO-WHEELED VEHICLES.

Specification of Letters Patent No. 18,077, dated September 1, 1857.

To all whom it may concern:

Be it known that I, PHILIPE BAILLAU, of New York city, in the county and State of New York, have invented certain novel and 5 useful Improvements in the Mode of Constructing Sulkies or other Two-Wheeled Carriages; and I hereby declare the following to be a full, clear, and exact description thereof, reference being had to the accompanying drawings, which are lettered to correspond with the specification and to form a 10 part of the same.

Description.—The nature of my invention consists in the method of attaching the thills 15 or shafts to the bearers or supporters (*d*.) of the body in such a manner that any vertical jar of the gig or sulky would not be felt by the horse, or on the other hand the constant jolting caused by the motion of the horse 20 would not be felt by the occupant of the vehicle as is the case with all the two wheeled carriages that are in common use.

The spring (*a, a, a*.) is a long flat piece of steel or a number of pieces or lifts arranged 25 similar to an ordinary compound spring used for carriages. I do not confine myself to any definite length of the spring or

springs (*a, a, a*.) Figures 1, 2, 3 as I prefer to use that which will be the most convenient to use with the different shapes of the bodies of the sulkies; spiral springs may be used but I prefer the flat spring to any other.

The spring (*a*) is secured to the bearers (*d*.) by means of a bolt and nut at the back end thereof as shown at (*f*) Fig. 2, the other 35 end being firmly fastened to the shafts. There is also (if desired) a flexible strap or spring (*e*) Fig. 2, that attaches the thill to the front end of the bearer (*d*) and prevents too great a strain upon the spring (*a*) which 40 may be caused by a sudden jar either from the horse stumbling or of the gig itself.

Therefore what I claim as my invention and desire to secure by Letters Patent of the United States is—

The flat spring (*a*) or its equivalent at the back end of the thills (*b*) arranged and operating in the manner and for the purpose substantially as described in the specification and shown in the drawings.

PHILIPE BAILLAU.
